UNITED STATES PATENT OFFICE.

CLAIR L. FARRAND, OF ELIZABETH, NEW JERSEY, ASSIGNOR, BY MESNE ASSIGNMENTS, TO RADIO CORPORATION OF AMERICA, A CORPORATION OF DELAWARE.

RADIO-TRANSMITTER.

1,385,818.

Specification of Letters Patent. Patented July 26, 1921.

Application filed June 14, 1919. Serial No. 304,290.

To all whom it may concern:

Be it known that I, CLAIR L. FARRAND, a citizen of the United States, and a resident of Elizabeth, county of Union, State of New Jersey, have invented certain new and useful Improvements in Radio-Transmitters, of which the following is a specification accompanied by drawings.

This invention relates to improvements in radio transmitters, employing a vacuum tube or tubes and oscillating circuits as the source of oscillations.

The primary object of the invention is to enable the maximum total electron emission of the filament to be utilized at all times, particularly in radio transmission, resulting in an increase in ratio of output to filament energy, and thereby increasing the efficiency of the tube. This increase in efficiency is especially advantageous and is a decided advantage in high power vacuum tubes in which the filament energy is appreciable.

The invention is applicable to several types of valves or vacuum tubes, as for instance the Weagant type having the heated filament and a plurality of cold elements or plates inside the tube, and a plurality of shields or influencing members outside the tube; or else the influencing members may be in the usual form of internal grids.

The invention is illustrated in the accompanying drawings, in which,

Figure 1 is a diagrammatic representation of circuits and apparatus for carrying out the invention in connection with a Weagant shield valve;

Fig. 2 illustrates graphically the electron current in an oscillating valve as normally used;

Fig. 3 illustrates graphically the maximum filament emission as obtained in accordance with my invention; and

Fig. 4 is a diagrammatic view similar to Fig. 1 showing a valve having all the elements inside the tube.

Referring to the drawings and at first more particularly to Fig. 1, the transmitting antenna A is provided with the usual variable inductance B, and is connected to ground at C. A transmitter key may be provided in any suitable location, as at D.

The oscillating vacuum valve E in this instance, comprises the evacuated tube F containing the heated filament G and the two cold plates H, while the influencing

members are in the form of external shields J and J' preferably surrounding the tube as indicated. The filament G is energized by the usual battery K.

In this instance a connection is made from a point adjacent the filament battery to a suitable point L on inductance coil B, and the source of plate current shown as a generator O, is conveniently connected between the filament and the plates H through the radio frequency supply choke coils P. By-path condensers Q are connected as shown between points on the plate circuits and the taps R on inductance B, and permit the oscillating currents to flow from the oscillator through that portion of the inductance B indicated by the position of the taps.

The shields or influencing members J and J' are connected respectively through the adjustable taps S and S' to points on inductance B at which the potentials will be substantially out of phase, preferably 180° out of phase for maximum efficiency.

In explaining the operation of the device, reference will be had to the graphic curves shown in Figs. 2 and 3. In Fig. 2 the curve U graphically represents the electron current in a three-element oscillating valve as normally used, that is with a heated filament, a cold plate and an influencing member or grid. It is apparent in such case that the filament must be supplied with sufficient energy to emit at all times electrons sufficient to supply the maximum of current.

Fig. 3 illustrates graphically the maximum filament emission as obtained in accordance with my invention. The curve V represents the electron current through one plate H as influenced by the shield J (or grid J² Fig. 4), and the curve W represents the electron current through the other plate H as influenced by the shield J' (or grid J³ Fig. 4). The two current curves as shown are 180° out of phase, and their summation is indicated approximately by the straight line X, corresponding to the maximum emission of the filament. By means of the circuits and connections illustrated, I am enabled to so increase the ratio of output to filament energy, that I obtain at all times substantially the maximum total electron emission of which the valve is capable.

Fig. 4 is a modification of Fig. 1, showing influencing members in the form of internal grids J² and J³ instead of external shields,

and otherwise the circuits are the same and the device operates in the same manner described, except that sources of negative potential in the form of batteries T are shown 5 in circuit with the grids.

I claim and desire to obtain by Letters Patent the following:

1. In radio transmitting apparatus, the combination of a vacuum valve having a 10 heated cathode, a plurality of cold elements or plates, a plurality of plate circuits and connections for causing said vacuum valve to generate oscillations in the plate circuits, an antenna, an inductance coil connected in 15 the antenna and plate circuits and a plurality of influencing members connected to points on said inductance coil at which the potentials are substantially out of phase.
2. In radio transmitting apparatus, the

combination of a vacuum valve having a 20 heated cathode, a plurality of cold elements or plates, a plurality of plate circuits and connections for causing said vacuum valve to generate oscillations in the plate circuits, an antenna, an inductance coil connected in 25 the antenna and plate circuits and a plurality of influencing members connected to points on said inductance coil at which the potentials are substantially 180° out of phase.

In testimony whereof I have signed this specification in the presence of two subscribing witnesses.

CLAIR L. FARRAND.
